FOREIGN PATENT DOCUMENTS

EM 003121060-0001 7/2016

Primary Examiner — Cynthia R Underwood(74) *Attorney, Agent, or Firm* — Reichel Stohry LLP;
Natalie J. Dean; Mark C. Reichel(57) **CLAIM**

The ornamental design for a dinner plate, as shown and described.

DESCRIPTION

FIG. 1 is a top perspective view of a dinner plate of the present disclosure according to at least one embodiment; FIG. 2 is a bottom perspective view of the dinner plate of FIG. 1;

FIG. 3 is a top view of the dinner plate of FIG. 1; FIG. 4 is a bottom view of the dinner plate of FIG. 1; FIG. 5 is a front elevational view of the dinner plate of FIG. 1;

FIG. 6 is a side elevational view of a first side of the dinner plate of FIG. 1; and, FIG. 7 is a side elevational view of a second side of the dinner plate of FIG. 1.

The broken lines in FIGS. 1, 3, and 5-7 form no part of the claimed design.

1 Claim, 7 Drawing Sheets(56)
